UNITED STATES PATENT OFFICE

AXEL OSVALD APPELBERG, OF STOCKHOLM, SWEDEN, ASSIGNOR TO AKTIEBOLAGET BIRKA REGULATOR, OF STOCKHOLM, SWEDEN, A JOINT-STOCK COMPANY OF SWEDEN

ELECTRIC SWITCH

Original application filed September 21, 1921, Serial No. 502,301, and in Sweden September 30, 1920.
Divided and this application filed March 21, 1923. Serial No. 626,674.

This invention relates to electric switches and more particularly to periodical switches.

The damaging effect of the break sparks on the switch contacts is a great disadvantage, especially in periodical switches, in which the breaking of the current occurs at short intervals during long periods, and limits the use of such switches.

In accordance with the present invention the break sparks are eliminated to an essential degree by making the contacts of tungsten, molybdenum, tantalum or other refractory metal comparable therewith and disposing them in a receptacle, which is either evacuated or filled with an inert gas or gaseous mixture at suitable pressure. Preferably, a highly evacuated receptacle is used but receptacles filled with gas such as nitrogen, argon, neon, hydrogen or the like can also be used.

The favourable result obtained by the present invention in regard to the durability of the contacts and their capability of breaking even comparatively strong currents is mainly attributed to the combined effect of the vacuum and the high evaporating temperature of the contact metal, whereby the arcing is rendered more difficult and thus the breaking takes place quicker although the contacts may have a slow movement. This last mentioned quality renders the invention especially suitable for thermostatic switches, but it can also be used in other kinds of breakers.

On account of the great durability of the breaking contacts the device is particularly suitable for periodical switches of every kind, for instance limiting switches, switches for flash lights, and self-interrupting devices, especially thermostatic ones for regulating the supply of current to electric heating apparatus and the like.

One embodiment of the invention is shown in the accompanying drawing to which reference will now be made.

The two contacts 1, 2 are arranged at the free ends of two contact tongues 3, 4 fused in one end of a tube or bulb, which is evacuated or filled with an inert gas, one of said tongues, 4, consisting of a stiff plate and the

other consisting of two metallic laminae soldered together, said laminae having different co-efficients of expansion and forming a so called bi-metal or "thermostat-metal". On an increase in the surrounding temperature the thermostat 3 bends outwards from the stiff plate 4 until its outer end, on the attainment of a predetermined temperature, deflects said tongue and moves the contact 1 away from the contact 2. The contacts 1, 2 are of tungsten, or other metal comparable therewith and having a high temperature of gasification.

As applied to heating apparatus the switch is brought in thermic connection with the heat emitting part of the apparatus or the substance to be heated, and is included in the heating circuit so that it acts as a self interrupter, breaking the circuit when it exceeds a certain temperature and allowing only such a quantity of energy to pass as is sufficient to maintain said temperature.

When used as a current limiting device the bimetallic tongue 3 may be provided with a heating coil 6. Said heating coil is preferably inserted in series with the main electric circuit.

Owing to its small dimensions a device of this character is easily applicable to current consuming apparatus as generally used and wherein the strength of current shall not exceed a certain limit. For example, such current supply limiting devices may be arranged in lamp holders, the consumption being limited to lamps of a certain maximum of luminous intensity.

What I claim as new and desire to secure by Letters Patent of the United States of America is:

1. A thermostatic switch sealed in an evacuated receptacle and consisting of a bi-metallic stem, a switch member co-operating therewith, a heating winding on said bi-metallic stem, break contacts consisting of refractory metal, and outer terminals connected with said bi-metallic stem and said switch member.

2. A current limiting device for light installations, consisting of a thermostatic switch having a heating winding included in

the lamp circuit, said switch consisting of a bi-metallic stem sealed in an evacuated receptacle, and provided with contacts consisting of tungsten.

3. A current limiting device for light installations consisting of a thermostatic switch having a heating winding included in the lamp circuit, said switch consisting of a bi-metallic stem sealed in an evacuated receptacle, and provided with contacts consisting of a refractory metal.

In testimony whereof I affix my signature.
AXEL OSVALD APPELBERG.
